DESIGN FOR A HIGHWAY SIGN

William Rossman, Pecos, Tex.

Application November 4, 1946, Serial No. 134,494

Term of patent 14 years

(Cl. D1—12)

To all whom it may concern:

Be it known that I, William Rossman, a citizen of the United States, residing at Pecos, in the county of Reeves and State of Texas, have invented a new, original, and ornamental Design for Highway Signs, of which the following is a specification, reference being had to the accompanying drawing, forming part thereof.

Figure 1 is a top plan view of the highway sign showing my new design.

Figure 2 is a front elevational view, and Figure 3 is an end elevational view thereof.

I claim:

The ornamental design for a highway sign, as shown.

WILLIAM ROSSMAN.
